Des. 222,247
Patented Oct. 12, 1971

222,247

SNOWMOBILE TRACK

Jules Perreault, Sherbrooke, Quebec, Canada, assignor to
Bombardier Limited, Valcourt, Quebec, Canada

Filed Jan. 27, 1970, Ser. No. 21,112

Term of patent 14 years

Int. Cl. D12—13

U.S. Cl. D14—24

FIG. 1.

FIG. 2.

FIG. 1 is a perspective view of a snowmobile track showing my new design, it being understood that the design continues through the belt indicated in light, full lines.

FIG. 2 is a cross-sectional view taken along line 2—2 of FIG. 1.

I claim:

The ornamental design for a snowmobile track, as shown and described.
